(57) CLAIM

The ornamental design for a hotel reservation desk, as shown and described.

DESCRIPTION

FIG. 1 is a perspective view of a hotel reservation desk showing our new design;

FIG. 2 is a front elevational view thereof;

FIG. 3 is a right side elevational view thereof;

FIG. 4 is a left side elevational thereof; and,

FIG. 5 is a top plan view thereof.

The rear view of the article forms no part of the claimed design.
